United States Patent Office.

ROYAL C. TAFT, WILLIAM B. WEEDEN, AND JAMES W. TAFT, OF PROVIDENCE, RHODE ISLAND.

Design No. 4,864, dated May 2, 1871.

DESIGN FOR WOVEN CLOTH.

The Schedule referred to in these Letters Patent and making part of the same.

all whom it may concern:

Be it known that we, ROYAL C. TAFT, WILLIAM WEEDEN, and JAMES W. TAFT, all of the city and county of Providence and State of Rhode Island, have invented a new and useful Design for Woven Fabrics, specially adapted to fancy cassimeres; and we do hereby declare that the following specification, taken in connection with the drawing furnished and forming part of the same, is a true, clear, and exact description thereof.

The drawing represents a face view of a piece of fabric woven with our design.

A in each case represents one of a series of warpwise stripes. Their groundwork may be of any desired color, upon which spots of a contrasting color are thrown, giving the stripe a mottled appearance.

B in each case represents one of another series of warpwise bar-stripes, of a width equal to and of a color contrasting with the groundwork of the stripe.

Faint lines of a contrasting color extend warpwise through the middle of these stripes B. These faint lines

are crossed at short intervals with weftwise lines of a corresponding character, dividing the stripe into bars or squares slightly oblong.

C in each instance represents one of still another series of stripes of a "corded" style, and a color contrasting with the groundwork of the stripes A and B.

These stripes C are interposed as dividing or separating lines between the mottled stripes A and bar-stripes B, producing a pleasing and striking effect.

Having thus described our design,

We claim as new and desire to secure by Letter Patent—

The design for fancy cassimeres, which consists of the mottled stripes A, alternating with the bar-stripe B, and the intervening corded stripes C, substantially as described.

ROYAL C. TAFT.
WM. B. WEEDEN.
JAMES W. TAFT.
